UNITED STATES PATENT OFFICE

MAYHEW E. NOYES, OF CANTON, OHIO

ADJUSTABLE WINDOW SCREEN

Application filed November 9, 1928. Serial No. 318,127.

This invention relates to adjustable window screens and the object of the invention is to provide a window screen including a frame arranged to allow a screen fabric to be readily attached thereto.

5 Another object of the invention is to provide an adjustable window screen consisting of two frame members slidable in relation to each other and provided with guide members arranged to hold the frame members in parallel relation at all times.

10 A further object of the invention is to provide an adjustable window screen in which the frame is formed of sheet metal and arranged to receive a wire rod by which the screen is secured to the frame, the frame being arranged with a part engaging over the wire rod to retain the wire rod therein and secure the screen to the frame.

15 These objects and the several novel features of the invention are hereinafter more fully described and claimed and the preferred form of construction by which these objects are attained is shown in the accompanying drawings in which—

Fig. 1 is an elevation of an adjustable window screen embodying my invention.

Fig. 2 is an enlarged section taken on line 2—2 of Fig. 1.

30 Fig. 3 is an enlarged section taken on line 3—3 of Fig. 1.

Fig. 4 is an enlarged section taken on line 4—4 of Fig. 1.

Fig. 5 is an enlarged section taken on line 5—5 of Fig. 1.

Fig. 6 is a perspective view of an alternative form of wire rod for securing the screen in the frame.

Fig. 7 is a section taken on line 7—7 of Fig. 5.

Fig. 8 is a perspective view of an alternative form of guide member.

Fig. 9 is a section taken on line 9—9 of Fig. 1.

45 Fig. 10 is a perspective view of one frame member.

Fig. 11 is a perspective view of the other frame member.

The screen consists of two frame members 50 1 and 2 which are slidable in relation to each

other to accommodate the device for windows of different widths and the screen is usually placed in the window frame and the window sash is moved down into contact with the upper edge of the screen frame. The frame member 1, as shown in Fig. 4, is provided with a depending flange 3 at the outer edge terminating in an inwardly bent flange 4. At the opposite edge the frame member 1 is bent to form a depending U shaped channel 5 having an inturned outer edge 6 bent downwardly at an angle into the U shaped channel. The frame member 2, as shown in Fig. 2, is provided with a channel shaped portion 7 which provides a U shaped channel 65 and the edge 8 of this portion is bent downwardly at an angle into the U shaped channel 7.

This frame member is also provided with a rib 9 at the opposite edge of the channel 7 and a portion 10 is provided having an inturned flange 11 as shown. The frame member 1 is shown in Fig. 11 while the frame member 2 is shown in Fig. 10. These frame members are each three sided as shown and the frame member 1 is provided with a cross bar 12 extending between the ends of the frame member and secured thereto as shown in Fig. 11. This cross member 12 as shown in Fig. 3, is provided with a U shaped channel 13 having an edge 14 bent downwardly into the channel at an angle. The frame member 2, as shown in Fig. 10, is provided with a cross bar 15 which, as shown in Fig. 3, is provided with a U shaped channel 16 having an edge or flange 17 bent downwardly into the U shaped channel at an angle. The frame members are positioned together with the ends overlapping as shown in Fig. 1. A guide member 18 is provided as shown in Fig. 5 which extends into the channel 19 formed in the frame member 1 and into the channel 20 formed in the frame member 2. This guide member is held in the channel 19 of the frame member 1 by means of the two lugs 21 struck downwardly into the channel at opposite ends of the member 18 as shown in Figs. 1, 5 and 7. This secures the guide members 18 in place in the opposite ends of the frame member 1 and the guide mem- 100

bers 18 ride on the rib 9 of the frame member 2 and are slidable in the channel 20 of the said frame member.

As shown in Fig. 9 a similar member 18 is secured in each end of the frame member 2 and is held in place therein by the lugs 22 struck up into the channel 20 of the frame member 2. These lugs 22 hold this member 18 in position in the channel 20 and the frame member 1 is slidable on the said member 18. When the frame members are drawn outwardly to the position shown in Fig. 1 the members 18 in the frame member 1 strike the members 18 in the frame member 2 and prevent the frame members from being pulled apart. In order to secure the screen to the frame the screen is laid over the frame and a series of four rods 23 shown in Fig. 1 are positioned on the edge of the screen in each frame and are forced downwardly into the bottom of the channels 5, 7, 13 and 15 and in being forced down to the bottom of these channels the inturned flanges 6, 8, 14 and 17 are sprung inwardly and then spring outwardly over the respective rods 23 thus preventing removal of the rods and securing the screen between the said rods and the edges of these inturned flanges. In this manner the screen is stretched tightly over the respective frame member and is firmly secured therein. If desired a rectangular wire rod 24, shown in Fig. 6, may be used in each frame in place of the four rods 23 and will perform the same function.

In Fig. 8 an alternative form of guide member is shown in which the guide member 18 is elongated equal to the full length of one of the frame members and the lower flange of the guide member 18 is cut away except for a small portion 25 which may be secured between the inturned lugs 22 of one frame member in the same manner as indicated in Fig. 9. In this form one guide member 18 is used for each side of the frame and the frame member 1 is slidable longitudinally thereof and in this case only two guide members 18 are provided in place of the four heretofore described.

From the foregoing description it becomes evident that the device is very simple and efficient in operation, is formed entirely of metal which will not warp or bind, provides a novel means for securing the screen to the frame and provides a device which accomplishes the objects described.

Having thus fully described my invention, its utility and mode of operation, what I claim and desire to secure by Letters Patent of the United States is—

1. In an adjustable window screen, a pair of frame members, a pair of guide members carried by each frame member and engaging for slidable movement in the other frame member, a pair of lugs struck up from the respective frame members at each end of each

guide member to prevent longitudinal movement of the guide members in relation to the respective frame members, the guide members of one frame member being adapted to engage the guide members of the other frame member to prevent the frame members from being pulled apart, a U shaped channel formed in the inner edge of each frame member having a free inner edge bent downwardly at an angle into the channel providing a yieldable strip, and a series of rods of greater diameter than the space between the downwardly bent edge and the opposite side of the U shaped channel adapted to be forced down into the channel past the said downwardly bent edge as and for the purpose described.

2. In an adjustable window screen, a pair of frame members, a pair of guides carried by each frame member and engaging the other frame member to allow one frame to slide upon the other, a U shaped channel formed in the inner edge of each frame member having a free inner edge bent downwardly at an angle into the channel providing a yieldable strip, a rod of greater diameter than the space between the downwardly bent edge and the opposite side of the U shaped channel, a screen fabric extending over the edge of the channel and the rod being inserted in the channel below the said downwardly bent edge to engage the screen fabric between the rod and the said edge.

3. In an adjustable window screen, a pair of frame members slidably mounted in relation to each other, each frame member being formed of sheet metal and being provided with a depending U shaped channel at its inner edge, one edge of the U shaped channel being bent downwardly at an angle into the channel providing a yieldable strip, a screen extending over the edge of the channel and a rod inserted in the channel below the downwardly bent edge to secure the screen between the rod and the said flange, the terminal edge of the yieldable strip being spaced from the bottom and opposite side wall of the channel a distance less than the diameter of the rod.

4. In an adjustable window screen, a pair of frame members slidably mounted in relation to each other, each frame member being formed of sheet metal and being provided with a U shaped channel at its inner edge, the inner edge of the U shaped channel terminating in a portion bent downwardly into the channel as and for the purpose described.

In testimony whereof I sign this specification.

MAYHEW E. NOYES.
